US00D898754S

(12) United States Design Patent (10) Patent No.: US D898,754 S
(45) Date of Patent: * Oct. 13, 2020

(54) DISPLAY SCREEN OR PORTION THEREOF
WITH GRAPHICAL USER INTERFACE

(71) Applicant: Samsung Electronics Co., Ltd., Suwon-si (KR)

(72) Inventors: Jin Hee Jeon, Seongnam-si (KR); Hayoung Kim, Seoul (KR); Jieun Yang, Seoul (KR)

(73) Assignee: SAMSUNG ELECTRONICS CO., LTD., Suwon-si (KR)

() Term: 15 Years

(21) Appl. No.: 29/654,575

(22) Filed: Jun. 26, 2018

Related U.S. Application Data

(63) Continuation of application No. 29/590,745, filed on Jan. 12, 2017, now Pat. No. Des. 823,329.

(30) Foreign Application Priority Data

Jul. 29, 2016 (KR) 30-2016-0037225

(51) LOC (12) Cl. 14-04

(52) U.S. Cl.

USPC D14/486

CLAIM

The ornamental design for a display screen or portion thereof with graphical user interface, as shown and described.

DESCRIPTION

The FIGURE is a front view of a display screen or portion thereof with graphical user interface showing our new design.

The outer perimeter illustrated by broken lines in the drawing illustrates a display screen or portion thereof and forms no part of the claimed design. The remaining broken lines in the drawing illustrate portions of the graphical user interface that form no part of the claimed design.
